UNITED STATES PATENT OFFICE.

WILLIAM RICHARDS, OF AKRON, OHIO.

MAIL-LOADER.

1,032,775.

Specification of Letters Patent. Patented July 16, 1912.

Application filed April 6, 1912. Serial No. 688,992.

To all whom it may concern:

Be it known that I, WILLIAM RICHARDS, a citizen of the United States, residing at Akron, in the county of Summit, State of Ohio, have invented certain new and useful Improvements in Mail-Loaders; and I do hereby declare the following to be a full, clear, and exact description of the invention, such as will enable others skilled in the art to which it appertains to make and use the same.

This invention relates to mail loaders, and has for its object to provide an apparatus of this character adapted to project a bag containing mail from a casing or housing arranged adjacent the track.

A further object of the invention is to so construct the apparatus that the bag of mail will be projected from the housing into the door of a moving car.

With these and other objects in view, the invention consists in certain novel features of construction, combination and arrangement of parts as will be hereinafter fully described and claimed.

In the drawings: Figure 1 is a view showing the device in position to project mail into the door of a passing car. Fig. 2 is a front view of the loader with the end of the casing removed. Fig. 3 is an end view of the loader. Fig. 4 is a sectional view on line 4-4 of Fig. 2. Fig. 5 is a vertical transverse sectional view through the casing and loader showing the tripping mechanism in a position previous to the release thereof. Fig. 6 is a similar view, the tripping mechanism being shown after the same has been released by the passing car.

The loading device consists of a casing 1 which is adapted to be arranged adjacent the track. Upon the top of the casing 1 is mounted a housing 2, and has its end which is disposed toward the track open.

Slidably mounted in the housing 2 is a bag container 3, which consists of a bottom 4, side walls 5 and an end wall 6. Extending transversely of the end wall 6 is a bar 7, the opposite ends of which are projected a short distance beyond the sides of the housing 2, and are adapted for travel in slots 8 formed in the sides of the housing, and extend approximately half the distance thereof.

Arranged upon both sides of the open end 55 of the housing 2 are bolts 9, said bolts being provided with eyes 10. Connected to the

eyes 10 are the inner ends of coil springs 11, the outer ends of which being secured in perforations 12 formed in the ends of the bar 7, said springs serving to project the 60 bag container 3 forwardly in the housing when released.

Pivotedly mounted near the upper end of the rear wall of the casing 1, and interiorly thereof, is a lever 13, and to which is pivotally connected the lower end of a pin 14, the upper end of which extends a short distance above the top of the casing, and is beveled, as at 15, to more readily engage the socket plate 16 carried by the end wall 6 of 70 the housing 2, the upward movement of said pin being limited by the projected ends of a transversely arranged pin 17 carried by the pin 14.

To one end of the lever 13 is secured the 75 upper end of a coil spring 18, the lower end of which being secured to the rear wall of the casing 1. The other end of the lever 13 is provided with an offset 19 which is adapted to be engaged by and disengaged from 80 the hooked upper end 20 of the vertically sliding bar 21, the same being mounted in guides 22 carried by the rear wall of the casing 1.

Extending into the bottom of the casing 1 85 is a rock shaft 23 having formed upon its inner end the short arm 24, and to which is pivotally connected the lower end of a link 25, the upper end of said link being similarly connected intermediate the ends of 90 the bar 21.

Extending upwardly from the outer end of the shaft 23 is a trip arm 26, and in a convenient position to be engaged by a passing car. The trip arm 26 is so formed as to produce 95 a loop 27 to facilitate the displacement of the arm 26 by the arm 28 which is pivotally connected to one side of the car 30. The arm 28 is so formed that its inner end may be conveniently engaged by a latch 31 carried by the end wall of the car 30, so that the same may be held in a position to engage the loop 27 of the trip 26, when the car is in motion.

Pivotedly connected to the casing 1, and 105 adjacent the hooked end 20 of the bar 21 is an angle arm 32, one end of which engages the bar 21, and is held in yielding contact therewith by a coil spring 33, one end of which is connected to the other end of the angle arm 32, the lower end of said spring being secured to the rear wall of the casing 110 -

1. Thus it will be seen that the arm 32 will cause the hook 20 to yieldably engage the offset 19 formed upon one end of the lever 13.

5 From this construction, it will be seen that when the arm 28 carried by a passing car engages the loop 27, the shaft 23 will be rocked, and through the link 25 the bar 21 will be drawn downwardly until the hook 20 thereof disengages from the offset 19 carried by the lever 13, and at which time the pin 14 has been withdrawn from engagement with the socket plate 16, whereupon the bag container 3 will move rapidly 10 forward in the housing 2 and project a mail bag through the open door of the passing car. To reset the tripping mechanism, it is only necessary to reverse the movement of the parts, whereupon the hook 20 will engage 15 the offset 19, and the parts are in a position as shown in Fig. 5.

What is claimed is:

1. A mail loader comprising a casing, a housing mounted upon the casing and having an open end, slots formed in the sides of the housing, a bag container movable in the housing, a transverse bar carried by the container and operable in said slots, coil springs connecting the ends of the bar and 20 housing, a pin carried by the casing and adapted to engage the container, means car-

ried in the casing adapted to be actuated by a moving car to disengage the pin from the container, whereby said springs operate to move the container forwardly in the housing to eject a mail bag therefrom into the moving car. 35

2. A mail loader comprising a casing, a housing mounted upon the casing, a bag container movable in the housing, springs connected to the container and housing, a pin carried by the casing and adapted to engage the container to hold the same against the tension of said springs, a lever pivotally mounted in the casing and similarly connected to said pin, an offset carried by one end of the lever, a vertically slid able bar carried by the casing and having a hook formed upon its upper end for engagement by and disengagement from said offset, a 40 rock shaft carried by the casing, a link connecting the rock shaft and bar, yieldable means for positively causing engagement of the offset by said hook, said rock shaft being adapted to be actuated by a moving car to 45 operate the lever to release the container. 50

In testimony whereof, I affix my signature, in presence of two witnesses.

WILLIAM RICHARDS.
